(57) **CLAIM**

The ornamental design for implantable housing, as shown and described.

DESCRIPTION

FIG. 1 is a perspective view of an implantable housing showing our new design;

FIG. 2 is a front elevational view thereof;

FIG. 3 is a top plan view thereof;

FIG. 4 is a bottom plan view thereof;

FIG. 5 is a rear elevational view thereof;

FIG. 6 is a left elevational view thereof; and,

FIG. 7 is a right elevational view thereof.

The broken line shown in the drawings is included for the purpose of illustrating structural environment and forms no part of the claimed design.
